UNITED STATES PATENT OFFICE.

EDWARD C. CHAPPELLE, OF CORNING, NEW YORK.

PIPE OR FLUE CONNECTION FOR HOT-AIR FURNACES.

1,158,786.

Specification of Letters Patent.

Patented Nov. 2, 1915.

Application filed March 6, 1915. Serial No. 12,611.

To all whom it may concern:

Be it known that I, EDWARD C. CHAPPELLE, a citizen of the United States, residing at Corning, in the county of Steuben and State 5 of New York, have invented certain new and useful Improvements in Pipe or Flue Connections for Hot-Air Furnaces, of which the following is a specification, reference being had to the accompanying drawings.

10 This invention relates to an improved pipe or flue connection for hot air furnaces and has for its primary object to provide improved means for connecting a plurality of flues leading from the several compartments of a building to the bonnet of a furnace at the center thereof.

15 It is a more particular object of the present invention to provide square or rectangular heat conducting flues whereby the same may be compactly fitted or nested in an upstanding collar or flange on the bonnet of the furnace so that the heat rising from the fuel bed will be equally distributed to the several flues.

20 25 The invention has for a further general object to improve the flue connection for hot air furnaces in the manner above referred to, whereby a maximum amount of heat will be obtained from a minimum consumption 30 of fuel, the invention, as a whole, being simple in its construction, inexpensive to produce, and highly efficient and serviceable in practical operation.

With the above and other objects in view, 35 my invention consists in the novel features of construction, combination, and arrangement of parts to be hereinafter more fully described, claimed, and illustrated in the accompanying drawing, in which,

40 Figure 1 is an elevation of a furnace, partly in section, illustrating my improved pipe or flue connection; and Fig. 2 is a section taken on the line 2—2 of Fig. 1.

In the illustrated embodiment of my invention, 45 5 designates the hot air furnace which may be of any ordinary type and is provided at its upper end with the tapering bonnet or hood 6 into which the heat is received and directed into the several flues.

50 I provide this hood with the upstanding rectangular wall or flange 7.

8 designates the conducting flues or pipes which are of rectangular form in cross-

section, and as shown in Fig. 2, have one of their ends fitted within the upstanding wall 55 7. The rectangular flues are of such dimensions that when all of the same have been fitted into the collar or flange 7 on the hood 6, they will be very compactly or tightly nested therein, so that no air space 60 will remain between the several flues 8 through which the hot air might escape into the furnace room. The other ends of the several flues 8 are, of course, extended to the wall registers of the several apartments 65 in the usual manner. It is apparent that when a greater or less number of flues than is shown in the drawing are necessary, the form and proportion of the upstanding collar 7 will be changed accordingly. 70

In hot air furnaces, as generally constructed, the flues or pipes extend radially from the collecting chamber in the upper end of the furnace, and there is an unequal distribution of the hot air to these flues. 75 The draft through the furnace causes a direct upward movement of the hot air from the center of the fuel bed, and it is, therefore, obvious that, by extending the flues directly into the top of the heat collecting 80 chamber at its center, a maximum quantity of the hot air from the interior of the furnace will be distributed in approximately equal proportions to the several flues. In this manner, I obtain a maximum supply of 85 hot air from a minimum consumption of fuel so that all of the various compartments in the building to which the flues are connected will be uniformly heated.

From the foregoing description, taken in 90 connection with the accompanying drawing, the construction, manner of operation, and several advantages of my invention will be clearly and fully understood. The device is applicable to the several types of hot 95 air furnaces now in common use without necessitating any material alterations in the same. It will, however, be understood that the invention is susceptible of considerable modification in the form, proportion and 100 arrangement of its several structural features and I, therefore, reserve the privilege of adopting all such legitimate modifications as may be fairly embodied within the spirit and scope of the invention as claimed. 105

Having thus fully described my inven-

tion, what I desire to claim and secure by Letters Patent is:—

The combination with a hot air furnace provided with a bonnet having an upstanding rectangular collar, of a plurality of air conducting flues of rectangular form in cross-section having one of their ends fitted within said collar, the said ends of the flues

being frictionally engaged with each other and with the walls of the collar.

In testimony whereof I hereunto affix my signature in the presence of two witnesses.

EDWARD C. CHAPPELLE.
